UNITED STATES PATENT OFFICE

2,201,985

DISPENSING CABINET

Bearl E. Colburn, Green Bay, Wis.

Application November 8, 1938, Serial No. 239,537

3 Claims. (Cl. 40—63)

The invention relates to cabinets especially adapted for use for dispensing purposes, the primary object of the invention being the provision of means in such cabinets for displaying advertisements or the like.

Another object of the invention is the provision of a construction of the character indicated so arranged as to permit the ready insertion or removal of advertising matter for display.

Other objects will appear hereinafter.

The invention consists in the combinations and arrangements of parts hereinafter described and claimed.

The invention will be best understood by reference to the accompanying drawing forming a part of this specification and in which

Fig. 1 is a front perspective view of a dispensing cabinet embodying the invention;

Fig. 2 is a partial front view of the same;

Fig. 3 a section taken substantially on line 3—3 of Fig. 2;

Fig. 4 a section taken substantially on line 4—4 of Fig. 2; and

Fig. 5 a section taken substantially on line 5—5 of Fig. 2.

The embodiment of the invention illustrated in the drawing comprises a rectangular cabinet 10 made of sheet metal having a vertical front wall 11 provided adjacent its bottom with a discharge slot or opening 12 for the dispensing of paper towels in strip form.

The front wall 11 of the cabinet is provided with a central sight opening 13 which is rectangular in form and has its greater dimension arranged horizontal as shown. The edges 14 of the opening 13 are bent or "struck" outwardly to form an ornamental border for the opening 13 and a retaining recess 15 on the inner side of the wall 11. Vertical retaining strips 16 are arranged on the inner side of the wall 11 as shown to traverse the opposite edges of the sight opening 13, said strips being secured at both top and bottom to the wall 11, but free therefrom at their outer edges as indicated. A flexible transparent sheet 17 is arranged as shown in the recess 15 and a display card 18 is also arranged in said recess immediately behind said transparent sheet 17. A metallic retaining plate 19 is arranged as shown immediately behind the display card 18 with its edges inserted under the adjacent edges of the retaining strips 16, and whereby said display card 18 will be nicely and snugly held in place.

By this arrangement display cards for advertising or other purposes may be readily inserted in or removed from the recess 15 behind the transparent plate 17. For this purpose, if the display card is sufficiently flexible so that it may be

bent centrally without injury, its edges may be readily inserted under the strips 16. If the display card is stiffer or not capable of being bent, one of its edges may be slipped under one of the strips 16 and thence outwardly under the outer free edge of said strip to permit the insertion of the other edge under the other strip 16 and thus placed in position in the recess 15 behind the transparent plate 17. The retaining plate 19 may be readily placed in position by having its edges inserted under the adjacent edges of the strips 16 as indicated. Obviously the parts may be correspondingly and readily removed when desired. The specific form and arrangement of parts disclosed is a simple and effective one for the purpose.

While I have illustrated and described the preferred form of construction for carrying the invention into effect, this is capable of variation and modification without departing from the spirit of the invention. I therefore do not wish to be limited to the precise details disclosed, but desire to avail myself of such variations and modifications as fall within the scope of the appended claims.

I claim:

1. A cabinet of the class described having a sheet metal front wall provided with a display opening having its edges bent outwardly to form an outer border for said opening and an inner recess to receive the edges of a display member; and two strips on the inner side of said wall traversing opposite edges of a display member in said recess.

2. A cabinet of the class described having a sheet metal front wall provided with a display opening having its edges bent outwardly to form an outer border for said opening and an inner recess to receive the edges of a display member, said opening being rectangular in form and arranged with its greater dimension horizontal; two vertical strips traversing opposite edges of a display member in said recess, said strips being secured at top and bottom to said wall but free therefrom at their outer edges.

3. A cabinet of the class described having a sheet metal front wall provided with a display opening having its edges bent outwardly to form an outer border for said opening and an inner recess to receive the edges of a display member; and means comprising vertical strips on the inner side of said wall for removably retaining a display member in said recess, and a plate fitting against the back of the display member and extending at each side beneath the edges of the vertical strips.

BEARL E. COLBURN.
